DICTATION TRANSCRIBING MACHINE OR SIMILAR ARTICLE

Gordon W. Florian, Fairfield, Conn., assignor to Dictaphone Corporation, Bridgeport, Conn., a corporation of New York

Application October 7, 1957, Serial No. 47,989

Term of patent 14 years

(Cl. D26—14)

FIG. 1.

FIG. 2.

FIG. 3.

Fig. 1 is a perspective view of a dictation transcribing machine or similar article, showing my new design; Fig. 2 is a side elevational view; and

Fig. 3 is a rear elevational view thereof.

I claim:

The ornamental design for a dictation transcribing machine or similar article, substantially as shown.
